Primary Examiner — Garth Rademaker*Assistant Examiner* — Katie Stofko(74) *Attorney, Agent, or Firm* — Greenberg Traurig, LLP(57) **CLAIM**

The ornamental design for a food product, as shown and described.

DESCRIPTION

FIG. 1 is a perspective view of a food product showing my new design;

FIG. 2 is a front view of the food product shown in FIG. 1; FIG. 3 is a rear view of the food product shown in FIG. 1; FIG. 4 is a left side view of the food product shown in FIG. 1;

FIG. 5 is a right side view of the food product shown in FIG. 1;

FIG. 6 is a top view of the food product shown in FIG. 1; and,

FIG. 7 is a bottom view of the food product shown in FIG. 1.

The broken lines shown in FIGS. 1-7 illustrate portions of the food product that form no part of the claimed design.

1 Claim, 7 Drawing Sheets(56)
